[57] CLAIM

The ornamental design for an armchair, as shown and described.

DESCRIPTION

FIG. 1 is a perspective view of an armchair incorporating my design and showing the side and front;
FIG. 2 is a side perspective view of the armchair of FIG. 1 looking slightly downwardly so as to see the top at a sharp angle; and,
FIG. 3 is a rear elevation of the chair.
The side of the chair not shown is a mirror image of the side shown in FIG. 2.
